UNITED STATES PATENT OFFICE.

FRANK E. BRYAN, OF NILES, OHIO.

TROLLEY-WHEEL.

No. 797,342.

Specification of Letters Patent.

Patented Aug. 15, 1905.

Application filed December 24, 1904. Serial No. 238,184.

To all whom it may concern:

Be it known that I, FRANK E. BRYAN, a citizen of the United States of America, residing at Niles, in the county of Trumbull and State of Ohio, have invented certain new and useful Improvements in Trolley-Wheels, of which the following is a specification, reference being had therein to the accompanying drawings.

This invention relates to certain new and useful improvements in trolley-wheels, and has for its object the provision of a novel form of wheel which will automatically replace a trolley-wheel in its proper position should the same become displaced therefrom.

It is a well-known fact that the trolley-wheels now in use at times become displaced from the trolley-wires on account of the cars carrying the same rapidly passing around a curve or the trolley-wheel engaging the guide-wires or obstacles that are in the path of travel of said wheel. The wheel as constructed by me aims to dispense with the trouble experienced with wheels now in use, and in constructing my improved wheel I slightly change the construction of the harps now used by making the same of a sufficient width to accommodate my improved trolley-wheel.

The invention finally consists in the novel construction, combination, and arrangement of parts, which will be hereinafter more fully described and then specifically pointed out in the claim, and referring to the drawings accompanying this application, like numerals of reference designate corresponding parts throughout the several views, in which—

Figure 1 is a side elevation of my improved trolley-wheel, illustrating the same mounted in a harp. Fig. 2 is an end view of the same. Fig. 3 is a side elevation view of my improved trolley-wheel. Figs. 4 to 6, inclusive, are views illustrating different elevations of my improved trolley-wheel.

To put my invention into practice, I employ a harp 1, which is constructed upon lines similar to harps now used, with the exception that the same is made of a sufficient width to accommodate my improved trolley-wheel.

The trolley-wheel in its entirety is designated by the reference-numeral 2 and is journaled in the harp 1 by the ordinary form of pin 3. The periphery of the wheel is formed with three grooves 4, 5, and 6. These grooves in cross-section are of a substantially U shape, and the groove 5 is adapted to normally receive the trolley-wire (not shown) upon which

the wheel travels. My invention resides in the particular formation of these grooves, and that the same may be clearly understood I will describe each groove independently and their relation to one another. The one end 7 of the groove (designated by 4) terminates in the edge of the wheel, while the opposite end of the groove, as indicated by 8, terminates in the groove 5. The junction of the groove 4 with the groove 5 forms a surface which the trolley-wire can readily engage and be transferred from the groove 4 to the groove 5 should the trolley-wire become displaced from the groove 5 and ride upon the groove 4. The one end 9 of the groove 6 terminates in the opposite edge of the trolley-wheel from that of the groove 4, and its other end terminates in the groove 5, as indicated at 10. The termination of the grooves 4 and 6 within the groove 5 are at different points of the periphery of the wheel. This particular arrangement of the grooves and their terminations enables the grooves 4 and 6 to rapidly return the trolley-wire to its proper groove—namely, the groove 5—should the wire become displaced and travel in either of the grooves 4 or 6.

The ordinary construction of the trolley-poles and their spring-actuated mechanism causes the trolley-wheel to at all times engage the trolley-wire, and the grooves 4 and 6 will be forced into engagement with the trolley-wire should the wire become displaced from the groove 5.

It will be seen from the foregoing description, taken in connection with the drawings, that I have provided a novel trolley-wire-replacing device in the form of a trolley-wheel which is extremely simple in construction, strong and durable, and highly efficient for the purposes above specified, and while I have herein illustrated the grooves of the trolley-wheel and their terminations as being of one particular formation it is obvious that I may construct a trolley-wheel having a plurality of grooves therein, the grooves all terminating in a central groove in which the trolley-wire is normally adapted to travel.

It will be noted that various other changes may be made in the details of construction without departing from the general spirit and scope of the invention.

What I claim, and desire to secure by Letters Patent, is—

A trolley-wheel having a central trolley-wire groove which is continuous around the

wheel, and an auxiliary groove at each side of the trolley-wire groove, the auxiliary grooves being of less depth than the trolley-wire groove, but parallel with the said trolley-wire groove throughout the major part of their circumference, said auxiliary grooves merging at one end into the trolley-wire groove at opposite sides of the wheel, the other end of said auxiliary grooves being

closed by the wall between the auxiliary grooves and the trolley-wire groove, extended across and joined with the rim of the wheel.

In testimony whereof I affix my signature in the presence of two witnesses.

FRANK E. BRYAN.
